(57) **CLAIM**

The ornamental design for a battery case, as shown and described.

DESCRIPTION

FIG. 1 is a perspective view of a battery case;
FIG. 2 is a perspective view of the battery case;
FIG. 3 is a perspective view of the battery case;
FIG. 4 is a perspective view of the battery case;
FIG. 5 is a front view of the battery case;
FIG. 6 is a back view of the battery case;
FIG. 7 is a left side view of the battery case;
FIG. 8 is a right side view of the battery case;
FIG. 9 is a bottom view of the battery case; and,
FIG. 10 is a top view of the battery case.

The broken lines show portions of the battery case in which the design is embodied, or applied to, that form no part of the claimed design. Surface shading is included to depict the three-dimensional aspects of the design.
